UNITED STATES PATENT OFFICE.

JOHN McC. LOCKHART, OF CORAOPOLIS, PENNSYLVANIA.

MOP.

1,073,612.

Specification of Letters Patent. Patented Sept. 23, 1913.

Application filed May 15, 1912. Serial No. 697,488.

To all whom it may concern:

Be it known that I, JOHN McC. LOCKHART, a citizen of the United States, residing at Coraopolis, in the county of Allegheny and State of Pennsylvania, have invented certain new and useful Improvements in Mops, of which the following is a specification.

My invention has for its object to provide a mop comprising a clamp for the mop material, a handle, and a securing ferrule or clamp, adapted for easy and quick connection and separation, and so designed as to effect economy in the cotton strands or other material used.

The device is illustrated in the accompanying drawings, in which—

Figure 1 is a view of the complete mop, in elevation. Fig. 2 is an enlarged vertical 20 sectional view through the clamping ferrule, handle and clamp. Fig. 3 is a cross section on the line III. III. of Fig. 2. Fig. 4 is an assembled perspective view showing the wire clamps. Fig. 5 is a view similar to 25 Fig. 2 illustrating a modified construction. Fig. 6 is a vertical section of the ferrule used in the construction of Fig. 5 at right angles thereto. Fig. 7 is a cross section on the line VII. VII. of Fig. 5.

The operative or working portion of the 30 mop is the head 2 consisting of an assembled mass of strands of loosely woven cotton or the like. They are collectively held at their middle portions in a closely 35 clamped central head portion by a wire clamp, illustrated in detail in Fig. 4. Thus, the clamp is made of a strand of wire having one or more coils 3 normally spaced apart as at 4 and having extended securing 40 side pieces or horns 5, 5, for attachment to the handle 6. In the construction shown in the principal figures of the drawing the horns 5 terminate in inwardly turned studs 7, 7, adapted to extend into receiving sockets 8 at opposite sides of the handle. The cotton strands are passed diametrically 45 through the spaces 4 and the coils 3 are then closely drawn together and secured by holding clips or catches 9. The horns 5 are bent outwardly at their middle portions as indicated at 10, in rounded form, for the purpose of making interlocking engagement 50 with the ferrule 11. Said ferrule is tubular in form adapted to slidably embrace the handle 6, and is preferably flared or flanged 55

at the bottom, as at 12, forming a broad solid bearing against the assembled strands at the middle of the mop head. The ferrule is grooved longitudinally along each opposite inner side, as at 13, to receive the 60 horns 5, and is also apertured through the sides, as at 14, for clearance of the outwardly bowed projections 10. In connecting the parts together, the horns 5 of the mop head are first passed over the end of 65 the handle 6 and the studs 7 are inserted in sockets 8. The ferrule 11 is then lowered over the horns, embracing them at each side by grooves 13, sufficient force being exerted to force the bowed projections 10 inwardly 70 until they spring out through apertures 14. These apertures are so located as to register with the projections when the flange 12 is pressed tightly against the mop head, and by springing out through the apertures the 75 projections act as keys to securely lock the ferrule in position on the handle, in connection with the insertion of the studs 7 in openings 8. It will be understood that the 80 mop as thus constructed is ready for use. When the head 2 is worn out, it is removed by merely forcing the ferrule back, and replacing a new head and clamp and connecting it with the handle by the ferrule in the 85 manner described.

In the construction shown in Figs. 5, 6, and 7 the head and clamps are substantially the same in construction except that the horns 5' are straight and terminate in hooks 7' turned in reverse directions. The ferrule 11' is continuous without apertures at the side, but having continuous oppositely located longitudinal grooves 13', while the interior cavity is partly closed at the bottom by a flange 15 at a slight distance above the edge of the outer flaring flange 12'. The handle 6' is provided with oppositely located pins 16, 16, and between the inner end of the handle and flange 15 is inserted a coiled spring 17. The parts being assembled, handle 6' is forced inwardly against the spring 17 sufficient to lower pins 16 below the hooks 7' and the handle is then turned in the manner of making a bayonet joint and allowed to recede under spring pressure, thus snugly seating the pins against the hooks 7', as indicated in dotted lines in Fig. 6.

It will be understood that each head and its wire clamp is complete as a unit and 110

may be collectively discarded when the mop head is worn out, or the clamp may be again used with new strands, if preferred.

An especial advantage of the clamp construction is its great simplicity and strength and economy of cotton strands. Thus the strands, by being merely laid straight across between the spirals 3, are of the shortest possible length, utilizing the smallest possible 5 part of the middle for attachment, and effecting a great saving in material. The clamping connection is very tight and efficient. The holding action of the ferrule is continuously maintained. The parts are 10 rigidly held in position, and the device as a whole is very efficient for the objects in view.

It will be understood that the invention may be changed or varied in different details or proportions by the skilled mechanic, 15 but all such changes are contemplated as within the scope of the following claims.

What I claim is:

1. A mop head consisting of a securing clamp formed of a continuous wire having 20 its endmost portion composed of a plurality 25

of overlapping spirally arranged coils and bent outwardly therefrom to provide extended handle portions, an assemblage of mop strands fixedly embraced by said coils, and means holding said coils tightly together and in embracing engagement with the mop strands, substantially as set forth. 30

2. A mop head consisting of a series of strands and a securing clamp having a middle spirally arranged portion engaging the 35 strands, securing clips holding the spiral portion in tight engagement with the strands, and extended securing horns, substantially as set forth.

3. A securing clamp for a mop head consisting of a wire formed to provide a middle spirally arranged portion and extended attaching horns, substantially as set forth. 40

In testimony whereof I hereunto affix my signature in the presence of two witnesses. 45

JOHN McC. LOCKHART.
